INVENTOR

EDWARD LESCH.

ATTORNEY

UNITED STATES PATENT OFFICE.

EDWARD LESCH, OF NEW YORK, N. Y.

COLLAR-BUTTON.

1,271,182.

Specification of Letters Patent. Patented July 2, 1918.

Application filed September 11, 1917. Serial No. 190,816.

To all whom it may concern:

Be it known that I, EDWARD LESCH, a citizen of the United States, residing at New York, in the county of New York and State 5 of New York, have invented certain new and useful Improvements in Collar-Buttons, of which the following is a specification.

This invention has relation to certain new and useful improvements in collar buttons 10 and has for its primary object the provision of a button which may be readily secured in position and securely held in place after being passed through the shirt-band and collar.

Another object of the invention resides in 15 the provision of a button of the above stated character which may be readily placed in position without injury to the shirt-band or collar and which will be formed of the 20 minimum number of parts of simple construction.

A further object of the invention resides in the provision of a button of the above stated character which will be constructed in 25 such manner that the button may be readily assembled, will be highly efficient in use and inexpensive to manufacture.

With these and other objects in view, as 30 will be apparent as the description proceeds, the invention consists in the novel construction, combination and arrangement of coöperating elements as will be hereinafter more 35 specifically set forth, pointed out in the claims and shown in the accompanying drawings.

In the drawings forming a part of this application and in which similar reference characters designate corresponding parts through the several views,

Figure 1 is a perspective view of my improved form of button in use,

Fig. 2 is an enlarged sectional view through the same,

Fig. 3 is a detail transverse section on the 45 plane of line 3—3 of Fig. 2 looking in the direction indicated by the arrows, and

Fig. 4 is a perspective view showing the manner in which the button is passed through the button hole.

Referring more particularly to the drawings, 50 1 designates the shank of the button, which is inclosed by a sleeve 2 which has a flange 3 formed upon its inner end and provided with a radial inwardly directed slot 4, 55 the parallel opposed walls 5 of the slot 4 being beveled on their upper faces. This

will make it possible to readily thread the flange 3 through the button hole. The flange 3 has a central opening 6 through which the shank 1 extends, as clearly shown 60 in Fig. 2. It will also be seen by referring to this figure that the outer end 7 of the sleeve 2 is rolled back to receive the turned back edge 8 of the separate head 9, which latter forms the end of the button. 65

The shank 1 is inserted in the sleeve 2 and passed through the opening 6 before the head 9 is placed in position. The reduced rear end 10 of the shank 1 is passed through a back plate 11 and then riveted to the same, 70 as shown at 12. A suitable spring 13 is engaged around the shank 1 within the sleeve 2 and has one end bearing against the flange 3 within said sleeve 2, while its opposite end bears against a flange or collar 14 mounted 75 on the forward end of the shank 1. As the spring 13 is under tension, the back plate 11 will be drawn toward the flange 3.

In use, the head 9 and sleeve 2 are forced 80 through the button hole and the button then turned to engage one of the beveled walls 5 with the button hole, whereby further rotation of the button will cause the wall to pass through the button hole, as shown in Fig. 4 and as the button continues to rotate, the entire flange 3 will be drawn through until the flange 3 rests upon one side of the material 85 through which the button hole is formed and the back plate 11 engages the opposite face, as shown clearly in Figs. 2 and 3 of the 90 drawings. The spring 13 will cause the flange 3 and back plate 11 to securely grip therebetween the material and thereby hold the button securely in proper position. It will be obvious that the button may be 95 passed in this manner through a number of button holes to secure together overlapped portions of a shirt-band or collar.

While the preferred embodiment of the invention has been shown and described, it 100 will be understood that minor changes in the details of construction and arrangement of parts may be resorted to within the scope of the appended claims without departing from the spirit of the invention or sacrificing any 105 of the advantages thereof.

I claim:

1. A collar button comprising a shank, a back plate carried by said shank, an inclosing member for said shank, said inclosing 110 member having a flange, and means engaged around said shank within said inclosing

member to cause the flange of said inclosing member and said back plate to grip a member through which the button is engaged.

5. 2. A collar button comprising a shank, a back plate carried by said shank, a sleeve surrounding said shank and carrying a radially slotted flange adapted to be threaded through a button hole through which the 10 sleeve is engaged, a button head mounted on said sleeve, and means for drawing together said back plate and said flange of the sleeve.

3. A collar button comprising a shank, 15 a back plate on said shank, a button hole entering member surrounding said shank, a slotted member carried by and forming a part of said button hole entering member, said slotted member being adapted to be 20 threaded through the button hole by rotation of the button hole entering member, means for causing said slotted member and said back plate to grip opposite faces of the material through which the button hole 25 is formed, and a head for said button.

4. A collar button comprising a sleeve

having a flange formed at one end and its opposite end rolled back, said flange having an inwardly directed radial slot with beveled walls to permit threading of the flange 30 through a button hole upon rotation of the sleeve, a back plate for coöperation with the flange to hold the button in position, means for forming resilient connections between said back plate and said flange, and a 35 head mounted on the turned back end of said sleeve.

5. A collar button comprising a sleeve, a head mounted upon one end of said sleeve, 40 a shank within said sleeve, a back plate mounted upon one end of said shank, said sleeve having a flange formed on one end, and means for forming a connection between said sleeve and said shank to cause the flange and the back plate to resiliently grip 45 a member positioned between the same.

In testimony whereof I affix my signature in presence of two witnesses.

EDWARD LESCH.
